EVAPORATIVE ODORIZER FOR GAS

Joseph F. Putnam, Berkeley, Calif., assignor to
 Standard Oil Company of California, San
 Francisco, Calif., a corporation of Delaware

Application August 20, 1938, Serial No. 225,950

6 Claims. (Cl. 261—65)

This invention relates to devices for introducing a volatile liquid material having a distinctive odor into a confined flowing stream of gas, and particularly refers to an apparatus for accurately controlling the rate of evaporation of a volatile odorant material and introducing the gas thus formed into a natural gas line at a rate substantially proportional to the rate of gas flow in said line and further controlled by the variations in density of the odorant material.

Those evaporative types of odorizers that have been used for this purpose are subject to atmospheric temperature variations that change the rate of evaporation of the liquid and hence the odorizing rate. It is well known that as a liquid odorant, particularly one which is not of a constant or nearly constant boiling mixture, is permitted to evaporate freely its density and also its rate of evaporation will change. Other factors, such as temperature variations, also have a detrimental effect upon the constancy of the rate of evaporation.

This invention comprehends broadly an improved evaporative type odorizer in which means are provided for varying the rate of gas flow through the odorizer in accordance with variations in the density of the liquid odorant which is being evaporated. This action includes a modification of the rate at which gas may be by-passed from a gas main by means of an orifice therein, to pass through the evaporating chamber and there be partially or entirely saturated with the vaporized odorant liquid.

It is an object of this invention to provide an evaporative type odorizer which will contain a minimum of moving parts and an entire absence of small passages, orifices, and the like.

A further object is to provide an evaporative odorizer in which variations in density of odorant liquid, for example, those caused by introducing a fresh charge of odorant liquid, temperature variations, and the like will be corrected by self-contained means so that a substantially constant odorizing rate will be maintained.

Another object is to provide an evaporative odorizer which will operate on very low pressure differentials and with a minimum of attention and maintenance.

These and other objects and advantages will be more fully apparent from the following description and from the drawing which forms a part of this specification and illustrates a preferred embodiment of the invention.

The drawing is a diagrammatic vertical sec-

tional view of an odorizer of this type applied to a natural gas line.

Referring to the drawing, the reference numeral 10 designates a gas line through which natural or other normally non-odorous gas is passing in the direction indicated by the arrows. A pressure differential producing means such as an orifice or gate valve 11 is positioned in the line 10 and serves to divert a portion of the gas through high-pressure conduit 12, into chamber 14 and back into line 10 through low-pressure conduit 13. This gas, being more or less saturated with volatilized odorant, will diffuse into the main gas stream and impart to it a distinctive and recognizable odor.

In order to supply a liquid odorant material to chamber 14 there is provided a storage tank 15, preferably elevated above chamber 14, and connected thereto by a conduit 16. In this example conduit 16 is provided with a float chamber 17 in which is mounted a small float 18 which controls a valve 19 to maintain a constant liquid level in chamber 14. If desired, float 18 could equally well be mounted in chamber 14 or some other means provided for holding a constant level in that chamber. To equalize the pressure between the vapor space in chamber 14 and that in tank 15, a pressure equalizing conduit 20 connects these two spaces. Tank 15 is preferably provided with a filling nozzle 21 and a gage glass 22. A similar gage glass 23 may be provided for evaporating chamber 14 to indicate whether or not the constant level means are functioning.

If the rate of evaporation of the odorant liquid is such that an extended wetted surface is desirable in chamber 14, this may be provided by a plurality of baffles 24, which may be of some capillary material such as cotton, woven asbestos, or the like.

In order to control the rate of gas flow through the vapor space of chamber 14, there is provided in conduit 13 a valve seat 25 in which is mounted a valve member 26 attached by means of a stem 27 to a float 28, the latter being guided by vertical members 29 to assume a position in the odorant liquid in chamber 14 according to the density of that liquid. By the construction just described an increase in density of the liquid which is normally accompanied by a decrease in its evaporation rate will cause float 28 to rise and open valve 26, thus permitting the pressure differential across orifice 11 to pass a greater quantity of gas through the vapor space of chamber 14. Conversely, if the density of the liquid should decrease as by an increase in temperature or by the

introduction of a fresh charge of odorant into tank 15, float 28 will sink in the liquid in chamber 14 and reduce the rate of gas flow through that chamber. In this example the valve is indicated as being within conduit 13 but it is obvious that it could equally well be positioned in conduit 12 or within chamber 14. Also, control valves for conduits 12, 13, 16 and 20 could be provided and will ordinarily be installed for convenience of operation and maintenance. As they form no part of this invention, they have not been illustrated or described.

Although a specific arrangement and construction of an apparatus embodying this invention have been described and illustrated above, it will be understood that many changes could be made therein without departing from the invention, and all such modifications as come within the scope of the appended claims are embraced 20 thereby.

I claim:

1. An evaporative odorizer comprising a closed chamber adapted to contain a liquid odorant, conduit means for passing a stream of gas into and through said chamber, and means including a valve means above the level of said liquid odorant liquid for controlling the flow of gas through said conduit means said density-responsive means being located without the path of gas passing through said chamber.

2. An evaporative type odorizer comprising an evaporating chamber, a liquid odorant inlet for said chamber, means for maintaining a constant odorant liquid level in said chamber, means for passing a stream of gas into and through said chamber, and means including a valve means above the level of said liquid odorant responsive

to the density of said odorant liquid for controlling the flow of gas through said last named means.

3. An evaporative type odorizer according to claim 2, with the addition of baffle means of capillary material in said chamber and adapted to be wet by said odorant to increase its rate of evaporation into said gas stream.

4. An evaporative type odorizer according to claim 2 in which said last named means comprise a float in said liquid and a valve responsive to the position of said float.

5. An evaporative type odorizer according to claim 2 in which said last named means comprise a float in said liquid and a valve responsive to said float, said float and valve arranged to decrease the gas flow rate through said chamber with a decrease in density of said liquid odorant.

6. An evaporative type odorizer comprising an evaporating chamber, an odorant storage tank, an outlet conduit connecting said tank to said chamber, a float valve for maintaining a constant liquid level in said chamber, a pressure equalizing conduit connecting the vapor spaces of said chamber and said tank, a gas inlet conduit for said chamber, a gas outlet conduit for said chamber at a point above the liquid level therein, said conduits adapted to be connected to a source of differential pressure, a valve for one of said gas conduits, and means in said chamber responsive to the density of the odorant liquid therein for controlling said valve, so constructed and arranged that the flow rate of gas passing through said chamber will be a function of the pressure differential impressed upon said conduits, and a function of the density of said odorant.

JOSEPH F. PUTNAM.
